ABSTRACT

There is disclosed herein a differential on-hook and off-hook detector for telephone switching systems using common battery signalling. A differential amplifier is coupled by two time constant circuits, each having a different time constant, to the subscriber line. The two time constant circuits and the differential amplifier cooperate to produce a positive output voltage when the resistance of the subscriber line changes from a first resistance (on-hook resistance) to a second resistance (off-hook resistance) and to produce a negative output voltage when the resistance of the subscriber line changes from the second resistance to the first resistance. A first circuit including a light emitting diode and a photo transistor is coupled to the output of the differential amplifier and is responsive to the positive output voltage to provide a binary "0" output signal when the hook switch changes from the on-hook state to the off-hook state. A second circuit including a light emitting diode and a photo transistor is coupled to the output of the differential amplifier to provide a binary "0" output when the hook switch changes from the off-hook state to the on-hook state.

ON-HOOK AND OFF-HOOK DETECTOR FOR TELEPHONE SWITCHING SYSTEMS

BACKGROUND OF THE INVENTION

This invention relates to telephone switching systems using common battery signalling and more particularly to an on-hook and off-hook detector for employment in such systems.

Presently employed on-hook and off-hook detectors for telephone switching systems using common battery signalling use a circuit to sense the resistance of the subscriber's line. This prior art circuit operates such that when the line resistance exceeds a fixed threshold, on-hook resistance, an on-hook indication is generated, while when the line resistance is less than a fixed threshold, off-hook resistance, an off-hook indication is generated.

As the subscriber line becomes longer and longer, the on-hook resistance becomes less than the on-hook threshold and the off-hook resistance becomes greater than the off-hook threshold. Under these conditions, no indications can be generated and the switch system fails to function properly. Environmental conditions will aggravate the operation of the detector. Since the length of the subscriber line and the operating environmental condition can vary tremendously, the prior art detector cannot reliably detect a change in the hook switch under all conditions and cannot be used by the automatic switching system to indicate when a subscriber wants service, has answered a call or has terminated a call.

SUMMARY OF THE INVENTION

An object of the present invention is to provide an on-hook and off-hook detector for telephone switching systems using common battery signalling which overcomes the disadvantage of the above-mentioned prior art detectors.

Another object of this invention is to provide a differential on-hook and off-hook detector for telephone switching systems using common battery signalling which is especially adaptable to long field wire line applications.

Still another object of this invention is to provide a differential on-hook and off-hook detector for telephone switching systems using common battery signalling which adjusts to all line conditions in less than a second and operates on a sudden change in the line resistance only.

A feature of the present invention is the provision of a differential on-hook and off-hook detector for telephone switching systems using common battery signalling comprising: a subscriber hook switch; a battery having first and second terminals; a subscriber line coupled to the battery and the hook switch, the line having a first resistance when the hook switch is in an on-hook state and a second resistance when the hook switch is in an off-hook state; a first time constant circuit coupled to the line, the first time constant circuit having a first time constant; a second time constant circuit coupled to the line, the second time constant circuit having

a second time constant less than the first time constant; a differential amplifier having an output, a negative input coupled to the first time constant circuit and a positive input coupled to the second time constant circuit; the first and second time constant circuits and the differential amplifier cooperating to produce a positive output voltage when the resistance of the line changes from the first resistance to the second resistance and to produce a negative output voltage when the resistance of the line changes from the second resistance to the first resistance; first means coupled to the output of the differential amplifier responsive to the positive output voltage to provide a first output signal when the hook switch changes from the on-hook state to the off-hook state; and second means coupled to the output of the differential amplifier responsive to the negative output voltage to provide a second output signal when the hook switch changes from the off-hook state to the on-hook state.

BRIEF DESCRIPTION OF THE DRAWING

The above-mentioned and other features and objects of this invention and the manner of obtaining them will become more apparent by reference to the following disclosure taken in conjunction with the drawing, the single FIGURE of which is a schematic diagram of an on-hook and off-hook detector in accordance with the principles of the present invention.

DESCRIPTION OF THE PREFERRED EMBODIMENT

The differential on-hook and off-hook detector illustrated in the drawing adjusts to all line conditions in less than a second and operates on a sudden change in the line resistance only. Hence, this detector can be used to provide a reliable indication to an automatic switching system that a subscriber wants service, has answered a call or has terminated a call.

The detector illustrated in the drawing will not react to very rapid pulses or surges caused by lightning and radiation due to the time constant circuit including capacitor C_2 .

There is presented hereinbelow a list of design formulas that are useful in determining the values of the various electrical components illustrated in the drawing and also useful in explaining the operation of the on-hook and off-hook detector of the present invention.

DESIGN FORMULAS

L_B = feeding bridge inductance

C_B = feeding bridge capacitance

R_s = series line resistance

R_p = line leakage resistance

R_t = phone resistance

t = time

R_{L1} = on-hook state = $\frac{1}{2} (R_s + R_p)$

R_{L2} = off-hook state = $\frac{1}{2} R_s$

$$\left[R_s + \frac{R_p R_t}{R_p + R_t} \right]$$

$$R_t = \frac{1}{2} (R_1 + R_2)$$

LINE RESPONSE — DETECTOR INPUT VOLTAGE

$$V_o(t) = \frac{-V}{\left(1 + \frac{R_s}{R_c} + \frac{R_p}{R_{L2}}\right)} \left\{ 1 - \left[1 - \frac{a^t B}{2R_{L2}} \left(1 - \frac{p R_p}{-V} \right) \right] e^{-at} \right\}$$

$$e^{-at} = \text{exponential}$$

$$a = \frac{2}{L_B} \left(R_{L2} + \frac{R_s R_c}{R_s + R_c} \right) = \text{reciprocal of line time constant}$$

$$p = \frac{\frac{2}{L_B} \left(1 + \frac{R_s}{R_c} \right) + R_c}{R_c} = \text{current in inductor at } t = 0$$

$$V_h = p R_{L1} = \text{detector input voltage at } t = 0$$

DETECTOR RESPONSE

Detector Response

$$V_1(t) = \frac{R_2}{R_1 + R_2} [V_s(t) - (V_s(t) - V_h)e^{-a1t}] = \text{slow RC response}$$

$$a_1 = \frac{1}{C_1} \left(\frac{1}{R_1} + \frac{1}{R_2} \right) = \text{reciprocal of detector slow time constant}$$

$$V_2(t) = \frac{R_2}{R_1 + R_2} [V_s(t) - (V_s(t) - V_h)e^{-a2t}] = \text{fast RC response}$$

$$a_2 = \frac{1}{C_2} \left(\frac{1}{R_1} + \frac{1}{R_2} \right) = \text{reciprocal of detector fast time constant}$$

$$V_{T1}(t) = \frac{R_{T1}}{R_{T1} + R_B} \left[\frac{R_F}{R_2} (V_1(t) - V_2(t) - V_{D1}) \right]$$

$$V_{T2}(t) = \frac{R_{T2}}{R_{T2} + R_B} \left[\frac{R_F}{R_2} (V_2(t) - V_1(t) - V_{D2}) \right]$$

With T_1 ON $I_{D01} = \frac{+V - V_{D01} - V_{T1}}{R_{D1}}$
 $I_{T01} = I_{D01} \times \text{CTR}$

With T_2 ON $I_{D02} = \frac{-V - V_{D02} - V_{T2}}{R_{D2}}$
 $I_{T02} = I_{D02} \times \text{CTR}$

CTR = current transfer ratio of optical coupler isolator

OCI = optical coupler isolator

The operation of the on-hook and off-hook detector of the present invention will now be described.

I. ON-HOOK TO OFF-HOOK STATE

A. Initial conditions (on-hook state, $t = 0$)

In this condition subscriber hook switch 1 is open and a steady state current, p , flows from terminal $+V$ through resistor R_s , inductor 2 of feeding bridge 3, the subscriber line including resistors R_s and R_p , inductor 4 of feeding bridge 3 and resistor R_e to terminal $-V$. Thus, the steady state current, p , flows through the line on-hook resistance developing a voltage input V_h to the detector including a first time constant circuit incorporating capacitor C_1 , a second time constant circuit including capacitor C_2 and differential amplifier 5, whose output is coupled to two circuits, one circuit to provide an indication for an off-hook condition and the other circuit to provide an indication for an on-hook condition. Under the above conditions,

$$V_1(O) = V_2(O) = \frac{R_2}{R_1 + R_2} V_h$$

This results in the differential amplifier 5 providing an output voltage $V_T = 0$, which results in a binary "1" output from each of the photo transistors T01 and T02.

B. Off-hook state

The hook switch 1 for the subscriber is closed and the line resistance instantly changes to the off-hook resistance by placing resistor R_s in parallel with R_p . The current in the line then changes as a function of time depending on the inductance L_B of feeding bridge 3 and the effective series resistance. A voltage V_s as a function of time is developed at the input of the detector in accordance with the design formula $V_s(t)$. Since capacitor C_1 and capacitor C_2 are charged to

$$\frac{R_2}{R_1 + R_2} V_h$$

these capacitors will change their charge as a function of time depending upon resistors R_1 and R_2 and the associated one of capacitors C_1 and C_2 . Voltage V_1 will change slowly according to the design formula $V_1(t)$ while voltage V_2 changes rapidly according to the design formula $V_2(t)$. If the time constant of the time constant circuit including capacitor C_1 is about 100

times greater than the time constant of the time constant circuit including capacitor C_2 , a voltage difference as a function of time is developed at the output of differential amplifier 5. Since voltage V_2 is charging capacitor C_2 faster than voltage V_1 is charging capacitor C_1 , the non-inverting or plus input of differential amplifier 5, which is connected to voltage V_2 , will be at a higher potential than the inverting or minus input of differential amplifier 5 connected to voltage V_1 . Since voltage V_2 is positive and dominant, the output voltage of the differential amplifier 5 will be positive. The output voltage of amplifier 5 is positive for an on-hook to off-hook change of state and hence, will be applied between the base and emitter of npn transistor T_1 . The voltage applied between the base and emitter of transistor T_1 is in accordance with design formula $V_{T1}(t)$. When the voltage V_{T1} is greater than the voltage between the base and emitter, V_{BE} , of transistor T_1 , this transistor turns on allowing current I_{D01} to flow from the positive terminal $+V$ to ground through resistor R_{D1} and light emitter diode D01. Current I_{D01} is translated to a proportional amount of light which is coupled through an optical coupled isolator OCI to photo transistor T01 which translates the received light to a current I_{T01} . Current I_{D01} is decreased by the current transfer ratio CTR such that $I_{T01} = I_{D01} \times \text{CTR}$. When the current I_{T01} is greater than 1.6 milliamperes transistor T01 turns on and a binary "0" is generated at the collector thereof to indicate an on-off hook state. Resistor R_{D1} is set so that $I_{D01} \times \text{CTR}$ is always greater than 1.6 milliamperes when transistor T_1 is turned on.

At approximately two times the time constant of the time constant circuit including capacitor C_1 , $V_1(t) \approx V_2(t)$ and the output voltage of amplifier 5 $V_T = 0$. When these conditions are present, transistor T_1 turns off and $I_{D01} = 0$, which turns off photo transistor T01 resulting in the generation of a binary "1" at the collector thereof.

The detector of this invention is now ready to detect an on-hook state when switch hook 1 is opened.

II. Off-Hook To On-Hook State

The detection of this change of state is the same as described above with respect to the change from the on-hook state to the off-hook state except in this case voltage V_1 is discharging capacitor C_1 slower than voltage V_2 is discharging capacitor C_2 . Thus, the inverting or minus input of the differential amplifier 5 connected to voltage V_1 is at a higher potential than the non-inverting or plus input of differential amplifier 5 connected to voltage V_2 . Since voltage V_1 is positive and dominant and is connected to the inverting input of the differential amplifier 5, the output of the differential amplifier 5 will be negative. The output of differential amplifier 5 is now negative so it will be applied between the base and emitter of pnp transistor T_2 via diode D_2 in accordance with the design formula $V_{T2}(t)$. Transistor T_02 is turned on in the same manner as described for transistor T_01 and a binary "0" output is generated at the collector of transistor T_02 to indicate an on-hook state.

The advantages of the detector of the present invention are as follows: (1) adjusts to changing line resistance, (2) detects only a rapid change in line resistance, (3) will not respond to extremely fast transients, (4) the detector can be made as sensitive as necessary by adjusting the gain of the differential amplifier 5 and (5) the steady state output voltage V_h can be used in an automatic gain control circuit to control the gain of the input and output amplifiers interfacing with the automatic switching system. This would allow longer lines to be used without degradation of signal level.

While I have described above the principles of my invention in connection with specific apparatus it is to be clearly understood that this description is made only by way of example and not as a limitation to the scope of my invention as set forth in the objects thereof and in the accompanying claims.

I claim:

1. A differential on-hook detector for telephone switching systems using common battery signalling comprising:
  - a subscriber hook switch;
  - a battery having first and second terminals;
  - a subscriber line coupled to said battery and said hook switch, said line having a first resistance when said hook switch is in an on-hook state and a second resistance when said hook switch is in an off-hook state;
  - a first time constant circuit coupled to said line, said first time constant circuit having a first time constant;
  - a second time constant circuit coupled to said line, said second time constant circuit having a second time constant less than said first time constant;
  - a differential amplifier having an output, a negative input coupled to said first time constant circuit and a positive input coupled to said second time constant circuit;
  - said first and second time constant circuits and said differential amplifier cooperating to produce a positive output voltage when the resistance of said line changes from said first resistance to said second resistance and to produce a negative output voltage when the resistance of said line changes from said second resistance to said first resistance;
  - first means coupled to said output of said differential amplifier responsive to said positive output voltage to provide a first output signal when said hook

- switch changes from said on-hook state to said off-hook state; and
2. A detector according to claim 1, wherein said first time constant is approximately one hundred times greater than said second time constant.
  3. A detector according to claim 1, wherein said first and second time constant circuits are resistorcapacitor time constant circuits.
  4. A detector according to claim 3, wherein said first time constant is approximately one hundred times greater than said second time constant.
  5. A detector according to claim 1, wherein each of said first and second output signals is a binary "0" condition.
  6. A detector according to claim 1, wherein said first means includes
    - a first diode coupled to said output of said differential amplifier,
    - a first transistor having its base coupled to said first diode, its emitter coupled to ground potential and its collector coupled to one of said first and second terminals of said battery through a first series circuit including a first resistor and a first light emitting diode,
    - a first optical coupler isolator coupled to said first light emitting diode, and
    - a first transistor circuit including a first photo transistor coupled to said first isolator to provide a binary "0" condition as said first output signal.
  7. A detector according to claim 6, wherein said second means includes
    - a second diode coupled to said output of said differential amplifier,
    - a second transistor having its base coupled to said second diode, its emitter coupled to ground potential and its collector coupled to the other of said first and second terminals of said battery through a second series circuit including a second resistor and a second light emitting diode,
    - a second optical coupler isolator coupled to said second light emitting diode, and
    - a second transistor circuit including a second photo transistor coupled to said second isolator to provide a binary "0" condition as said second output signal.
  8. A detector according to claim 7, wherein said first transistor is an npn transistor, and said second transistor is a pnp transistor.
  9. A detector according to claim 1, wherein said second means includes
    - a diode coupled to said output of said differential amplifier,
    - a transistor having its base coupled to said diode, its emitter coupled to ground potential and its collector coupled to one of said first and second terminals of said battery through a series circuit including a resistor and a light emitting diode,
    - an optical coupler isolator coupled to said light emitting diode, and
    - a transistor circuit including a photo transistor coupled to said isolator to provide a binary "0" condition as said second output signal.
